R. R. NOLEN.
MILL FOR GRINDING OR CRUSHING COTTON SEED OR THE LIKE.
APPLICATION FILED SEPT. 7, 1916.

1,224,406.

Patented May 1, 1917.

UNITED STATES PATENT OFFICE.

ROBERT RUFUS NOLEN, OF DALLAS, TEXAS.

MILL FOR GRINDING OR CRUSHING COTTON-SEED OR THE LIKE.

1,224,406.

Specification of Letters Patent.

Patented May 1, 1917.

Application filed September 7, 1916. Serial No 118,868.

To all whom it may concern:

Be it known that I, ROBERT R. NOLEN, a citizen of the United States, residing at Dallas, in the county of Dallas and State 5 of Texas, have invented certain new and useful Improvements in Mills for Grinding or Crushing Cotton-Seed or the like, of which the following is a specification.

My invention relates to improvements in 10 mills, for grinding or crushing material, such as cotton-seed, linseed or the like, and has particular reference to means for eliminating the hammering or jarring action ordinarily present during the operation of 15 such machines.

In the ordinary mill for grinding or crushing cotton-seed, linseed or the like, a plurality of vertically movable horizontal rolls are arranged one above the other, in 20 contacting relation. The lowermost roll supports or carries the combined weight of the upper rolls, which are adapted to partake of restricted vertical movements. The shaft carrying the lowermost roll, as 25 far as I am aware, has heretofore been journaled through stationary or fixed bearings. It was found that considerable power was necessary to operate these crushing mills, and to overcome this disadvantage, it was 30 proposed to provide the shaft of the lowermost roll with ball or roller bearings, and in some instances, to provide the shafts of the upper rolls with similar anti-friction bearings. These ball or roller bearings were 35 found to materially reduce the power required to drive the mill, but the ball or roller bearings were ordinarily quickly destroyed, due to the pounding or hammering action of the upper rolls upon each other and upon 40 the lowermost roll. In cotton-seed or the like, a certain amount of foreign matter is invariably present, such as hard bodies, comprising nails, and bits of iron, stone or the like. These hard bodies passing 45 between the rolls, cause the pounding or hammering effect upon the bearings, above referred to.

I have discovered that if the bearings for the shaft of the lowermost roll are yieldingly supported, such pounding or hammering action is absorbed, and the life of the bearings thereby prolonged. In this manner, ball or roller bearings may be advantageously employed, while the invention is 55 in no sense restricted to any particular form of bearings.

In the accompanying drawings forming a part of this specification and in which like numerals are employed to designate like parts throughout the same,

60

Figure 1 is a side elevation of apparatus embodying the invention,

Fig. 2 is an enlarged fragmentary side elevation of the same,

Fig. 3 is a vertical sectional view taken 65 on line 3—3 of Fig. 2, and,

Fig. 4 is a horizontal sectional view taken on 4—4 of Fig. 2.

In the drawings, wherein for the purpose of illustration is shown a preferred embodiment of my invention, the numeral 5 designates side frames, of which there are two. These frames are spaced and held stationary by any suitable means. Each frame 5 includes diagonal bars 6, extending from the 70 top to the bottom thereof. Arranged between these diagonal bars are preferably vertical guide means or guide-bars 7, included in the frame 5. The lower ends of the guide-bars 7 are preferably bent outwardly, forming horizontal portions 8. Connected with these horizontal portions 8 and the bottom of the frame 5 are lower vertical guide means or guide-bars 9, as shown.

Vertically movably mounted within the guide means or between the guide-bars 9 are bearings 10, which may be of any well known or preferred type, while they are preferably of the ball or roller type. Each bearing 10 comprises a body portion or casting 11, which contacts with the guide-bars 9. Arranged within the castings 11 are the ball bearings proper 12, through which are journaled the ends of the shaft 95 13 of the lowermost roll 14. The body portion or casting 11 of each bearing 10 rests upon or is supported by a transverse support-bar 15, preferably provided upon its upper surface with a curved recess, to receive the lower end of the body portion 11, as shown. The support-bar 15 has suitable connection with suitably stiff compression springs 17, engaging a lower support-bar 18, which engages the bottom of the frame. It is thus apparent that the bearings 10 are yieldingly supported in a manner to permit of their perceptible vertical movement. The rebound shocks are absorbed by 100 springs 18, engaging the tops of the bearings 10 and the horizontal extensions 8. 105

Arranged above the roll 14 are rolls 19,

these rolls contacting one with the other, whereby the roll 14 carries or supports the entire weight of the upper rolls. The upper rolls are provided with shafts 23, journaled 5 through vertically movable bearings 24, operating between the guide-bars 7. The bearings 24 may be ball or roller bearings, or any other suitable form of bearings.

The shaft 13 receives its rotation from a 10 pulley 25, and alternate shafts 23 receive rotation from pulleys 26, it being understood that these rolls may be driven by any other suitable means.

The cotton-seed or the like is fed into 15 the uppermost trough 27 from a hopper 28, and passes between the uppermost pair of rolls. By means of the succeeding-troughs 27, the material is caused to travel beneath each succeeding lower roll, until it is discharged 20 from the lowermost roll.

It is apparent that during the operation 25 of the machine, the upper rolls must be free to move vertically, to permit of the passage of the seed or the like therebetween, together with the solid bodies, such as pieces 30 of solid material. The lowermost roll being yieldingly supported, such yielding means properly absorbs the pounding and hammering, caused by the passage of the solid bodies between the rolls, which would otherwise be transmitted to the roller shafts and their bearings.

It is to be understood that the form of 35 my invention herewith shown and described is to be taken as a preferred example of the same, and that various changes in the shape, size, and arrangement of parts may be resorted to without departing from the spirit of my invention, or the scope of the subjoined claims.

Having thus described my invention, what I claim is:

1. In a machine of the character described, a frame comprising guide means, 45 a plurality of superposed rolls arranged to contact one with the other whereby the lowermost roll supports the combined weight of the upper rolls, a shaft carried by the lowermost roll, vertically movable bearings for the shaft arranged within the guide means, springs arranged beneath the vertically movable bearings to support them, springs arranged above the bearings to oppose their upward movement and take up rebound shocks, means whereby the upper rolls may move vertically with respect to the lowermost roll, means to feed material to be treated between the rolls, and means to drive the rolls.

60 2. In a machine of the character described, a frame comprising guide means, a plurality of superposed rolls arranged

to contact one with the other whereby the lowermost roll supports the combined weight of the upper rolls, a shaft carried 65 by the lowermost roll, vertically movable bearings for the shaft, blocks arranged beneath the lowermost bearings to contact therewith, springs arranged beneath the blocks to normally move the same upwardly, springs arranged above the lowermost bearings to contact therewith and to contact with a part of the frame to oppose upward movement and take up rebound shocks, means whereby the upper rolls may 70 move with respect to the lower rolls, means to feed material to be treated between the rolls, and means to drive the rolls.

3. In a machine of the character described, a frame comprising guide means, 80 a plurality of superposed rolls arranged to contact one with the other whereby the lowermost roll supports the combined weight of the upper rolls, a shaft carried by the lowermost roll; bearings for the 85 shaft; guides for the lowermost bearings, said guides being substantially wider than the guide means for the upper bearings whereby the said guides have upper horizontal portions, said bearings having their 90 tops formed flat and their lower faces rounded; blocks having concave upper faces adapted to contact with the rounded faces of the bearings, springs to move the blocks upwardly, springs to bear between the tops 95 of the bearings and the horizontal portion of the guide to oppose the upward movement of the bearings to take up rebound shocks, a hopper to feed material to the rolls; and means to drive the rolls.

4. In a machine for grinding seed containing hard foreign particles; an upstanding frame; a plurality of crushing rolls mounted in the frame, one above the other in contacting relation, so that the combined 105 weight of the upper rolls is carried by the lowermost roll, each roll being permanently vertically movable with respect to the frame, so that each roll may move away from its lower contacting roll upon the 110 passage of material therebetween; resilient means serving to support the lowermost roll whereby hammering caused by the passage of hard particles between the rolls is absorbed by the yielding means; means to 115 drive the rolls; and means to feed material to be treated therebetween.

In testimony whereof I affix my signature in presence of two witnesses.

ROBERT RUFUS NOLEN.
